(57) **CLAIM**

The ornamental design for a distal portion of hemostatic forceps for endoscope, as shown and described.

DESCRIPTION

FIG. 1 is a perspective view of the distal portion of hemostatic forceps for endoscope;

FIG. 2 is a top plan view thereof; the bottom plan view being identical thereto;

FIG. 3 is a front plan view thereof; the rear view being symmetrical thereto;

FIG. 4 is a left side view thereof;

FIG. 5 is a front view with the distal portion of hemostatic forceps slightly opened; the rear view being symmetrical thereto;

FIG. 6 is a left side view with the distal portion of hemostatic forceps slightly opened;

FIG. 7 is a top plan view with the distal portion of hemostatic forceps wide opened; the bottom plan view being identical thereto;

FIG. 8 is a front view with the distal portion of hemostatic forceps wide opened; the rear view being symmetrical thereto; and,

FIG. 9 is a left side view with the distal portion of hemostatic forceps wide opened.

The broken line showing is for illustrative purposes only and forms no part of the claimed design.
